UNITED STATES PATENT OFFICE

PAUL BOEHLAND, OF MILWAUKEE, WISCONSIN

DESIGN FOR A CHRISTMAS TREE ORNAMENT

Application filed March 5, 1931. Serial No. 38,951. Term of patent 14 years.

To all whom it may concern:

Be it known that I, PAUL BOEHLAND, a citizen of the United States, residing at Milwaukee, in the county of Milwaukee and State of Wisconsin, have invented a new, original, and ornamental Design for Christmas Tree Ornaments, of which the following is a specification, reference being had to the accompanying drawing, forming part thereof.

The drawing is a perspective view of the Christmas tree ornament embodying the invention.

I claim:

The ornamental design for a Christmas tree ornament as shown.

PAUL BOEHLAND.
